UNITED STATES PATENT OFFICE.

STEPHEN G. WRIGHT, OF OAK PARK, ILLINOIS.

ROOFING MATERIAL.

1,075,745.

Specification of Letters Patent.

Patented Oct. 14, 1913.

Application filed April 4, 1912. Serial No. 682,561.

To all whom it may concern:

Be it known that I, STEPHEN G. WRIGHT, a citizen of the United States, residing at Oak Park, in the county of Cook and State 5 of Illinois, have invented a new and useful Improvement in Roofing Material, of which the following is a specification.

My invention relates to improvement in prepared sheet-roofing having for its base a 10 sheet of fibrous material such as felt or paper, saturated and coated with bitumen, coal-tar, or other suitable organic or mineral wax and having a layer of water-resisting particles forming the weather-surface of the roof- 15 ing. In the manufacture of material of this character it is desirable that the exposed layers of wear-resisting particles be provided of different colors as desired, and various attempts have been made to manufacture, 20 within the limitations of cost which must be observed, roofing-material presenting a desirable shade of green, but such attempts have hitherto been unsuccessful.

My object is to produce roofing-material 25 having a wear-resisting layer of particles forming its weather-surface which shall present a desirable green coloring and which may be manufactured at relatively low cost.

The accompanying drawing illustrates a 30 sheet of roofing material made in accordance with my invention.

In the manufacture of my improved roofing, I employ a sheet 2 of felt, or other fibrous material, and treat it to a hot bath 35 of bitumen, coal tar or any other suitable organic or mineral wax, as is common practice, to saturate the fibrous sheet, and to produce on the upper surface thereof a coating of the bitumen, or other materials as 40 mentioned as represented at 3. I then spread upon the coating 3, while it is still hot, a surfacing of particles 4, and partially embed them in the coating by applying suitable pressure as by passing the sheets between 45 rollers.

In carrying out my invention I use for the surfacing 4 particles of any rock of the diorite-gabbro series, commonly known among miners and prospectors as "green- 50 stone," reduced, as by crushing, to preferably about 10 to 30 mesh, though the size of the particles 4 may vary, according to desire, from that stated. These particles 4 thus become embedded in the coating 3 and 55 are sufficiently close together to cause the

exposed surface of the roofing to present the color of the particles 4 as a substantially unbroken surface as to color. "Greenstone," in its natural condition, is of a grayish-green color, a color not desirable for roofing 60 surfaces, but I have discovered that by applying a fluid thereto, of a character substantially insoluble in water, which becomes absorbed by said stone, the color of the latter is changed from one not desirable for 65 roofing purposes, to a substantially permanent shade of green which is highly suitable for roof ornamentation.

Any desirable fluid which will resist dissolving when subjected to rain or snow may, 70 be used for this purpose and it may be brought into contact with the particles 4, for absorption thereby, in any desirable way, as for example, oil or any of the various mineral waxes or vegetable gums dissolved 75 in any light oil such as naphtha or in any other solvent may be used, or in fact any fluid possessing the properties above stated may be employed. It is preferred, however, that the fluid used be any desirable vegetable, 80 animal or mineral oil, as for example, a mineral oil of a specific gravity of about 33° Baumé.

In carrying out my invention the material forming the particles 4 either before or after 85 crushing and before application to the coating 3, may be treated to the said fluid in any desirable manner, or the particles 4 may be treated to the said fluid at a later stage in the process of manufacture. Thus the particles 4, spread on the coating 3, may be passed between rollers (not shown) covered 90 by cloth, or other suitable absorbent material, saturated with said fluid for application to the particles 4, or said fluid may be 95 applied to the particles 4 in any other desirable manner. If desired, said fluid for application to the particles 4, especially where said fluid be an oil, may be brought into contact therewith, for absorption thereby, by providing in the water-proof coating 3 for the base 2, during the manufacture of the material for said coating, or after the coating 3 has been applied to the base 2, a sufficient amount of oil of any desirable kind 100 to produce the desired absorption thereof by the particles 4 for rendering them of the desired shade of color. When the absorption by the particles 4 with oil is to be effected through contact of these particles with the 110

coating 3, care should be observed to insure the provision of the requisite amount of oil in the coating in order that the particles 4 take up sufficient oil to produce the desired shade of color in said particles; and should some of the coating materials as now commonly used inherently contain in the desired amount of oil for producing the change of color desired in the particles of "green-stone" (a condition which is considered detrimental to roofings as hitherto manufactured) the addition of oil to such coating-material will be rendered unnecessary. The application of said fluid to the particles 4 not only causes the roofing to present the desired shade of green, but the color produced is rendered substantially permanent and unchanging. It will be understood that, if de-

sired, the coating 3 and particles 4 may be applied to both sides of the base 2.

What I claim as new and desire to secure by Letters Patent is:

1. Roofing composed of sheet water-proof material having its weather-surface composed of particles of "greenstone," with oil, for the purpose set forth.

2. Roofing composed of sheet material coated with water-proofing material of the character described and a surface of particles of "greenstone," with oil, partially embedded in said coating, for the purpose set forth.

STEPHEN G. WRIGHT.
